HEAD ROD HOLDER

Jekum J. Munson, Milwaukee, Wis.

Application September 29, 1937, Serial No. 166,329

3 Claims. (Cl. 248—273)

This invention relates to improvements in head rod holders, especially, although not solely, adapted for use in connection with the pivotal support of the head rods of awning frames and the like.

It is customary to provide mounting hardware for awnings and the like which will permit movements of the awning frames for raising and lowering, and which will also permit removal of the awnings from the building at the end of the season. For this purpose, in addition to the other fixtures employed, there are interposed between the support and the awning frame head rod, certain fixtures known as head rod holders.

In the forms of head rod holders now in common use, each member consists of a bracket permanently attached to a face portion of the building. A clamping lug is adjustably connected to the bracket by means of a screw threaded clamp ing bolt extending into the bracket. In most instances when an awning is to be removed or mounted, the workman is positioned at an elevation on a ladder and is working under difficulties. With the prior type of head rod holder described, it is necessary, in order to make a connection or disconnection, that the clamping bolt be turned inwardly or outwardly to tighten or free the clamping lug which has to be swung into or out of position over the head rod. In most instances the clamping bolt and lug are hard to manipulate because of rust, corrosion, or stripped threads, and usually the workman has to apply pliers or a tool to these elements. Due to the position of the workman, this is usually extremely awkward and difficult and is sometimes dangerous in that he must retain his balance on the ladder and at the same time hold the awning frame and the tool which is being applied.

Recognizing the aforementioned objections to the former types of head rod holders, the present invention has for its object the provision of a bolt less head rod holder wherein connection and disconnection of the head rod relative to the fixture may be effected by a simple, quick manipulation with the use of tools.

A further object of the invention is to provide an improved head rod holder which eliminates the need of clamping bolts, winged nuts, and clamping brackets which were difficult of manipulation, and substitutes therefor an extremely simple and effective form of pivotal toggle latch which may be quickly manually manipulated with one hand without the use of tools.

A further object of the invention is to provide a head rod holder which, when engaging a head rod, provides for a secure attachment and will not become accidentally disengaged when an outward pull is imposed upon the head rod and frame.

A further object of the invention is to provide

a boltless head rod holder in which all portions thereof are integral, with no separate parts which might require removal with the consequent danger of loss.

Head rod holders are provided with depending hooked portions to engage the eyes of pulleys for the support of the latter. In working on awnings at an elevation, it is sometimes convenient for the workman to support himself by grasping one of the pulleys. With the constructions now in use if the pulley is accidentally pulled laterally, it may become detached from the hook portion of the holder whereby the workman will lose his means of support, which arrangement presents an objectionable hazard.

A further object of the present invention is to provide a head rod holder wherein the pulleys are detachably suspended therefrom in such a manner that they cannot become removed unless the same are passed through a certain passageway upwardly and laterally of the hook, minimizing the danger of the pulleys becoming detached from the holder if engaged for support by a workman.

A further object of the invention is to provide a head rod holder which is very simple in construction, is easy and quick to mount, connect, and manipulate, is inexpensive to manufacture, is strong and durable, and is well adapted for the purposes described.

With the above and other objects in view, the invention consists of the improved head rod holder, and all its parts and combinations, as set forth in the claims, and all equivalents thereof.

In the accompanying drawing in which the same reference characters designate the same parts in all of the views:

Fig. 1 is a front view of the improved head rod holder shown mounted against a supporting surface and operatively engaging the head rod of an awning frame;

Fig. 2 is a side view of the showing in Fig. 1 with the head rod and awning portion shown in section;

Fig. 3 is a top view of the showing in Fig. 1;

Fig. 4 is a front view of the head rod holder per se with the toggle latch mechanism in open or releasing position;

Fig. 5 is a sectional view taken on line 5—5 of Fig. 4; and

Fig. 6 is a view similar to Fig. 5, showing a modified form of the invention.

Although the invention is shown and described herein as forming a releasable mounting for the head rod of an awning frame, it should be understood that it is not the intent to thereby limit the scope of the invention, since the novel features of the device are obviously more generally applicable.

Referring now more particularly to the draw-

ing, it will appear that the improved head rod holder comprises a substantially T-shaped bracket with the upper portion forming opposite attaching ears 8 which are apertured to 5 permit the insertion therethrough of screws 9 for permanently securing the device against the surface of a support 10. Between said ears there are a pair of spaced ribs 11, with a recess or slot 12 therebetween. A pivot pin 13 is secured between the upper portions of said ribs, and another pivot pin 14 is secured between the lower portions of the ribs. A curved toggle latch 15 has its inner end pivotally mounted on the lower pin 14. The inner face of said latch is 15 curved on a radius, as at 16, while the outer or front face of the latch is provided with a shoulder 17. A locking dog 18, of curved formation, has its inner end pivotally mounted on the upper pin 13. Said dog is provided with a reduced and angularly shaped outer end portion 19 to engage the shoulder 17 of the latch when the latter is in its lowered position.

Below the ribs 11 the bracket is formed with a transverse semi-circular recess or socket 20 terminating in a forwardly directed flange 21. Depending from the flange is a hook 25 in the form of a G. Said hook is of sufficient size and is so proportioned as to permit its conveniently engaging the eyed portions or two or more pulley blocks 22. As will be seen from the drawing the pulley blocks normally depend from the bracket, and carry awning operating ropes 23. To prevent easy, undesired removal of a pulley block from the hook 21, it will be noted that the entrance 24 to the curved engaging portion of the hook is located upwardly and laterally of said engaging portion. Hence, removal of a pulley block can only be effected by moving the pulley block through an upward and lateral path, with the block turned horizontally.

The improved head rod holder is adapted to engage, for turning movement, the head rod 26 of an awning frame, the head rod having secured thereabout an edge portion of a canvas sheet 27. Inasmuch as it is customary to remove an awning from the building at the end of a season, it is necessary that the engagement between the bracket and the head rod be such that the head rod may be easily and quickly detached therefrom, it being remembered that the bracket or holder remains permanently attached to the building or support 10. For the support of an elongated head rod two or more holders are usually employed at spaced intervals. For the purpose of this explanation, however, the engagement and operation of only one head rod holder will be referred to.

When an awning frame head rod is to be secured in operative position, the latch 15 and dog 19 are both manually raised upwardly, as in Figs. 4 and 5. This exposes the bracket recess or socket 20, and a portion of the head rod, which is in horizontal position, is then lodged within said recess. The latch is then thrown downwardly over the outer portion of the head rod and because of the curved inner face, it, together with the socket, provides a substantially circular bearing for the rod, confining the same. To retain the latch in the down-turned securing position, the dog 18 is also thrown downwardly, and its end portion 19 engages the shoulder 17 of the latch. Thus, it will be seen that the head rod may turn within the socket, but because the latch is locked

in down-turned position, any outward pull or force cannot release the head rod from its mounting.

When, at the end of a season, it becomes desirable to remove the awning, it is of course necessary to detach the head rod from the bracket. This is accomplished by first turning the dog 18 upwardly to release the latch 15, after which the latch is turned to releasing position, permitting the entire removal of the head rod and associated parts.

In the modified form of the invention shown in Fig. 6, the latch 15' is formed similarly to the latch 15 of Fig. 5 except that its inner end is formed with a cam shaped rear extension 15''. The locking dog 18' is also formed similarly to the locking dog 18 of the principal form of the invention except that its inner end is provided with a rearward extension 18''. The purpose of this modified structure is to cause automatic movement of the latch to releasing position whenever the dog is moved out of engagement with the latch. Referring to Fig. 6, it is apparent that when the dog 18' is moved from the full line position to the dot-and-dash line position, that the extension 18'' will engage the cam portion 15'' of the latch 15' to automatically tilt the forward portion of the latch upwardly to releasing position.

It will thus be seen that with the improved head rod holder, the head rod may be easily and quickly mounted and removed without any inconvenience and without the use of tools. No screw threaded clamping members are utilized which can become rusted. The improved device is of simple and novel construction, and is well adapted for the purposes set forth.

What is claimed as the invention is:

1. A rod mounting device, comprising a bracket having a transverse recess in its front portion, a curved latch pivotally carried by the bracket and swingable over the recess to turnably enclose an element disposed in the recess, and a locking dog pivotally carried by the bracket and movable in the plane of movement of the latch for releasably engaging the latch to secure it in retaining position.

2. A rod mounting device, comprising a bracket having a transverse recess in its front portion, a curved latch pivotally carried by the bracket and swingable over the recess to turnably enclose an element disposed in the recess, a locking dog pivotally carried by the bracket and releasably engageable with the latch to secure it in retaining position, and means on said dog engageable with a portion of said latch for automatically moving the latch to releasing position when said dog is similarly moved.

3. A rod mounting device, comprising a bracket having a transverse recess in its front portion, a curved latch pivotally carried by the bracket and swingable over the recess to turnably enclose an element disposed in the recess, said latch having its inner end formed with a cam extension, and a locking dog pivotally carried by the bracket and releasably engageable with the latch to secure it in retaining position, said dog having its inner end formed with a rearward extension engageable with the cam extension of the latch to automatically move said latch to releasing position when said dog is similarly moved.
